CLAIM

The ornamental design for a utility vehicle, as shown and described.

DESCRIPTION

FIG. 1 is a front elevational view of a utility vehicle showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front and left side perspective view thereof;

FIG. 7 is a rear and left side perspective view thereof;

FIG. 8 is a front and right side perspective view thereof; and,

FIG. 9 is a rear and right side perspective view thereof.

1 Claim, 9 Drawing Sheets
